SEALING APPARATUS

Frank J. Malloy, Cleveland Heights, Ohio, assignor to General Electric Company, a corporation of New York

Application June 1, 1939, Serial No. 276,822

22 Claims. (Cl. 176—3)

My invention relates to sealing methods and apparatus generally, and more particularly to methods and apparatus for sealing together vitreous members or bodies forming an enclosure for an incandescent lamp or the like. The apparatus also preferably includes means for clearing said enclosure of air and contaminating gases. Still more particularly, my invention relates to apparatus for welding or sealing the preformed vitreous reflecting and refracting sections forming the enclosure or bulb of a lamp of the type disclosed in U. S. Patent No. 2,148,814, issued February 21, 1939, to D. K. Wright and assigned to the assignee of the present invention.

Electric lamps of the type disclosed in the above-mentioned patent comprise a pressed vitreous section which supports a filament or other light source and has a very definite interior shape, usually parabolic, with a reflecting coating thereon adapted to redirect the light from the filament in a definite manner. Over the mouth of the reflecting section, which has the form of a cup and constitutes one portion of the bulb, is sealed another vitreous cover or lens section constituting the other portion of the bulb and usually provided with light-refracting media or panels for concentrating or diffusing the light in a definite manner. To retain the advantages of this form of construction, the vitreous sections (cup and cover glass) must be sealed together satisfactorily while positively positioned with reference to each other, without injury to the reflecting coating or other parts of the lamp.

One object of my invention is to provide apparatus for automatically sealing the cover glass to the cup in a satisfactory manner at a relatively high rate of speed. Another object is to provide apparatus in combination with the afore-said apparatus for pre-heating the cover glass. Another object is to provide apparatus for positioning the cover glass with relation to the cup and forming the seal in a uniform shape during the sealing operations. Another object is to provide apparatus for re-positioning the cover glass with relation to the cup after the sealing operation to work the seal so as to relieve it of strains and to separate certain contacting but unsealed positioning surfaces on said cover glass and lens. These cooperating positioning surfaces are provided for the purpose of correctly positioning said cover glass and cup relatively to one another during the sealing operation, and are subsequently separated to obviate the tremendous strains which would otherwise be built up during the

cooling and contracting of the said cover glass and cup.

Another object of my invention is to provide a method and apparatus for protecting the reflecting coating on the inner surface of the cup during the sealing operation. This operation consists in flushing and filling the lamp enclosure with an inert gas at the start of the sealing operation so as to protect the heated coating from the atmosphere, and is equally useful in the sealing of blown vitreous bulbs having a reflecting coating thereon.

Still another object of my invention is to provide apparatus for clearing the lamp enclosure of whatever atmospheric and gas and vapor contamination it contains, directly after the sealing operation and preferably during the annealing of the lamp. This operation is preferably performed by flushing the enclosure with an inert gas, such as nitrogen, during the period said enclosure is heated, and has the advantage that the contamination driven from the lamp parts by heat, is withdrawn therefrom and the lamp filled with a gas which prevents further contamination even after the said lamp is removed from the sealing machine. Other features and advantages of my invention will appear from the following detailed description of a species thereof, and from the accompanying drawings.

In the drawings Fig. 1 is a plan view of a sealing machine comprising my invention; Fig. 2 is a vertical section through the cover glass pre-heating turret along the line 2—2 of Fig. 1; Fig. 3 is a vertical section through the sealing turret and a portion of the frame of the machine along line 3—3 of Fig. 1; Fig. 4 is a perspective view of the holders of the heads of the machine with the cup partly positioned therein and the pre-heating burners of station B of the turret shown in proper relation thereto; Fig. 5 is a perspective view of the cover glass positioning means at the sealing station E; Fig. 6 is a diagrammatic perspective view of actuating means for the burners and the seal working and reshaping means located at stations E, F, G, H and J; Fig. 7 is a side elevation, partially broken away, of burners and rolling means at station G for pressing a sealing flange of the cover glass into engagement with that of the cup; Fig. 8 is an end view of said rolling means; Fig. 9 is side elevation of operating means for the burners and rolling means at station G, and the actuating means shown in Fig. 6 for the burners and other means at stations E, F, H and J; Fig. 10 is a side ele-

vation, partially broken away, of burners and seal reshaping means at station J; Fig. 11 is an end view of said means; Fig. 12 is a side elevation of the cover glass repositioning means at station K; Fig. 13 is a plan view of the vertical adjustment means thereof; Fig. 14 is a perspective view of actuating mechanism of the repositioning means, and a valve for controlling the introduction of gas into the lamp engaged by said mechanism; and Fig. 15 is a plan view of jaws controlling the engagement of the adjusting means.

The machine disclosed in the drawings, automatically performs all functions required to seal the vitreous cover glass or lens 20 to the cup or reflector section 21 shown in section on a larger scale in Fig. 3, and in its preferred form provides a plurality of heads 22 (Fig. 1) on a separate turret 23 for carrying said cover glasses 20 to and from pre-heating means. The motion of the turret 23 is in a counterclockwise direction and advances each of the heads 22 in turn, into station A' which permits an operator located adjacent thereto to place one of the cover glasses in each head. As shown in Fig. 2, each cover glass 20 is placed in a head 22 so that a positioning shoulder or embossment 24 rests on the asbestos pads 25 on the three equidistantly spaced arms of the holder 26 which in turn is mounted on the hub 27. In order that the cover glass 20 can be rotated at other stations taken by the head 22, the hub 27 is mounted on the ball bearings 28 and 29 carried by the spindle 30 which is held by the flanged bushing 31 carried by the turret 23. The support for the turret 23 is provided by a second turret 32 (Figs. 1 and 3) directly below the former which provides a plurality of supporting standards 33 at regular intervals, and which is indexed as a unit therewith.

Following a definite period at station A', the head 22 is advanced to station B' and in so doing carries the teeth 34 on the hub 27 into engagement with the chain 35 which causes it to be rotated. The chain is introduced into the path of movement of the said teeth 34 of the hub 27, by the idler sprocket 36 and extends nearly completely around the machine, engaging, in turn, the teeth of the hubs 27 of the succeeding heads 22 (some of which are broken away from Fig. 1) before again passing onto a second idler sprocket 37 adjacent station C'. The sprockets 36 and 37 separate the chain 35 from the heads 22 during their stay at stations A' and C', so that said heads 22 are not turning at these stations, and direct said chain to and from the driving sprocket 38. Sprocket 38 is fastened to the shaft 39 which is mounted in the bracket 40 extending upward from an underlying portion of the frame 41 of the machine and is driven by the electric motor 42 through worm gears 43 and 44. Both the sprockets 36 and 37 are supported by bracket 40, although the latter is mounted on the relatively long arm 45 extending therefrom, and the former is carried by the yoke 46 attached to the mid portion of said arm 45.

The rotating movement of the heads 22 causes the upper and lower banks of burners 47 and 48 (Fig. 2) located at station B' and each of the succeeding stations, excepting station C', to be distributed to all portions of the cover glass 20. In this particular instance, the cover glass 20 is made of a low expansion glass, such as "Pyrex," which melts at a relatively high temperature, and four burners are included in each of the upper banks 47, and three burners are included

in each of the lower banks 48 to provide the necessary heat. Common manifolds 49 and 50 are provided for supporting and supplying the combustible gas mixture to each of the burners 47 and 48 respectively at each station, and separate manifolds (not shown) extending nearly around the machine in the usual manner, are preferably provided for supplying the gas and compressed air of said mixture. The parts of the heads 22 are protected from the heat by the asbestos plate 51 mounted over the turret 23, and the plates 52 mounted over the lower portions of the holders 26. An asbestos plate 53 is also mounted below the turret 23 to protect it somewhat from the sealing means located below.

Station C' is the unloading station and the pre-heated cover glass 20 is taken from the head 22 at this point and fed into the lower sealing portion of the machine.

The insertion of the cover glass 20 into the sealing portion of the machine, however, follows the introduction of the cup or reflector section 21, since said cover glass must be rested thereon, and is performed manually following the insertion of said cup into the head 54 at station A. The insertion of the cup is also performed manually and consists in resting the cup on the holder 55 (Figs. 3 and 4) which is, at this station, raised above the other apparatus of the head 54, as shown in Fig. 4. The holder 55 is mounted on the upper end of the hollow spindle 56 which is now supported by engagement of the shoe 57 on the lower end thereof with the highest part of the track 58. In placing the cup 21 on the holder 55, the said cup is carried down between the fingers 59 thereof in such a manner that the exhaust tube 60 extending therefrom is threaded over the end of the metal tube 61 and enters the passage 62 in said holder 55 and the spindle 56, and three lugs 63 located at unequally spaced intervals on the under side of the periphery of said cup 21 are rested on the upper ends of said fingers 59. Additional lugs 62'-62' are located on each side of each of the three lugs 63. The proper orientation of the cup 21 to cause the lugs 63 to fall on the fingers 59 is brought about by turning said cup 21 until the three unequally spaced cup-like metal terminal elements 64 on the under side thereof fall into three openings 55' in the holder 55 and the proper lug 63 drops between the locating stops 59' attached to the sides of one of the fingers 59. The cover glass 20 is then placed over the mouth of the cup 21 in a position determined, in a vertical direction, by the engagement of the annular shoulder or embossment 24 with the annular recessed reference seat 65 of the cup 21, the correct angular relationship of the cover glass to the cup and the terminal elements being predetermined by matching protuberances and depressions (not shown) in said embossment 24 and seat 65. The filament 66, having been previously located correctly with respect to the interior reflecting surface 67 and the recessed seat 65, automatically takes a definite position with reference to the various parts of the cover glass 20.

The sealing head 54, of which the holder 55 and the spindle 56 are a part, is automatically indexed from station A to station B, after the interval allowed for the feeding operations, by movement of the turret 32 which is mounted on the hollow column 68 at the center of the machine. The said turret 32, which, as shown, is

made up of two sections fastened together, rests on the flange 69 on the column 68, which in turn rests on the ball bearing 70 carried by the frame 41, and is indexed by mechanism engaging the lower end of said column 68, which mechanism is of conventional design and is not shown. The spindle 56 is located within a sleeve 71 carried by the turret 32, and, until advanced from station A, is kept from rotating by the roller 72 on the pulley 73 on the lower end of said sleeve 71, which roller engages the ways of the track 74 indicated therewith in Fig. 3. The sleeve 71 is locked to the spindle 56 through a key (not shown) entering a longitudinal groove in said spindle 56 so that both must be turned as a unit and are kept from rotating at station A to allow the operator to turn and adjust the cup 21 with respect to the holder 55 and spindle 56. The indexing movement of the head 54, however, carries the roller 72 beyond the end of the track 74 and brings the pulley 73 into engagement with moving belt 75 which causes it to rotate. The belt 75, as shown in Fig. 1, enters this portion of the machine from the idler pulley 76 and extends on around the pulleys 73 of the other heads 54 thereof until it is drawn off to a driven pulley 77 opposite station P. Idler pulley 76 corresponds to idler pulley 78, which receives the belt 75 from the driven pulley 77, in that it is mounted on a portion of the frame 41 and redirects said belt 75 to said idler pulley 76. The driven pulley 77 is fastened to a shaft 79 also supported by the frame 41 and is operated through said shaft 79 and the usual form of gear and chain drive means (not shown), engaging the main drive shaft of the machine located below the turret 32 along the dot-dash line 80.

The indexing movement from station A to B also repositions the cover glass 20 and cup 21 vertically as the spindle 56 is lowered by the movement of the shoe 57 on the end thereof down a sloping portion of the track 58 to the horizontal level 58' shown in Fig. 3, and causes the flushing and filling of the space enclosed by said cover glass and cup with an inert gas by adjustment of the rotary valve 81 at the center of the machine. The repositioning of the cover glass 20 and cup 21 locates these parts in correct operative relation to the upper and lower banks 82 and 83 (Fig. 1) of preheating burners at station B which burners, as shown in Figs. 1 and 4 respectively, are set so as to reach all parts of the cover glass 20 and cup 21. The repositioning motion also carries the opening 84 in the spindle 56 into alignment with the opening 85 in the sleeve 71 so that the inert gas can be introduced into the opening 62 in said spindle 56 and into the space enclosed by said cover glass 20 and cup 21. The function of the inert gas at this and immediately succeeding moments of operation when the cup 21 is heated, is to protect the reflecting coating 67 on the interior thereof from the oxidizing effect of the atmosphere. In this instance nitrogen gas is used and the source thereof is connected to an aperture corresponding to that shown at 86 in the lower half 87 of the rotary valve 81 aligned with the aperture 88 in the upper half 89 thereof, which is connected to the head 54 through the pipe 90. The gas leaving the pipe 90 enters a chamber 91 in a portion 70 of the turret 32 surrounding the sleeve 71 and flows through the openings 85 and 84 in said sleeve 71 and spindle 56, to the longitudinal passage 62 therein, which conducts it to the passage 92 in the block 93 and metal tube 61. The 75

block 93 closes the upper end of the passage 62 and supports the metal tube 61 which enters the cup 21 a short distance so as to keep the influx of gas separate from that escaping down the exhaust tube 60 of said cup 21 in the space about the metal tube 61. The gas passing out the exhaust tube 60 flows up the opening in the holder 55 and between the cup 21 and the top of said holder 55 which offer very little resistance thereto. The pre-heating operation performed at station B by the upper and lower banks 82 and 83 of burners, corresponds to the pre-heating operations carried on at stations C and D which are performed by duplicate banks of burners and like said operation, are coupled with the entrance of nitrogen into the cup 21 through the rotary valve 81. In each instance an aperture corresponding to aperture 86 is provided in the lower half 87 of the rotary valve 81 which rests on the frame 41 and which is held in a fixed position by the head of the screw 94 extending therefrom and the movement of the turret 32 indexing the head 54 turns the upper half 89 of the valve 81 so that the aperture 88 is in alignment therewith. The upper half 89 of the rotary valve 81 is caused to turn with the turret 32 by the pin 95 which extends into apertures in each, and is pressed against the lower half 87 in order to keep the adjacent faces thereof tight together by the spring 96. At these stations the cover glass 20 is pre-heated still further to a temperature that is still somewhat below the softening temperature thereof, and the cup 21 is pre-heated to an extent limited by the destructive effect of said heat on the reflecting coating 67 of aluminum, for instance.

Station E is the next station into which the head 54 is indexed in its regular order of movement and is the first of a series at which the actual sealing operations take place. In the course of movement of the head 54 to this station E, the shoe 57 on the end of the spindle 56 passes down the inclined portion 58'' of the track 58, causing said spindle 56 and the holder 55 to be lowered until the angular under surface 21' of the edge of the cup 21 rests on the ring-shaped holder 97 and supports said cup. At the limit of movement of the spindle 56, the shoe 57 passes beyond the end of the track 58 and is supported by the engagement of the flange 98 thereon with the arms 99 extending from the sleeve 71. This motion of the spindle 56 is more than is required to place the cup 21 on the ring-shaped holder 97 and it carries the fingers 59 down into recesses in said ring-shaped holder 97 so that all portions of the holder 55 are separated slightly from the cup 21. The positioning lugs 63-62' on the cup 21 fall into the notches 97' in the ring-shaped holder 97 but do not rest thereon. The holder 97 also functions as a centralizing means for the cup 21 as the more oblique sides of said cup engage said holder 97 when off center so it automatically shifts into place.

The ring-shaped holder 97 is mounted on the bracket 100 on the standards 101 carried by the arms 99 of sleeve 71, which in turn engages the turret 32 through the ball bearing 102. Before the head 54 is moved into station E, the cover glass 20 is not necessarily located centrally on the cup 21 but as it comes into said station, the outer edge or flange 114 of said cover glass engages the top flange 103' on the positioning roller 103 and the cover glass is pushed back to the correct position as the head 54 revolves. The roller 103, as shown in Figs. 1, 3 and 5, is rotatably mounted on

the pin 104 extending from the arm 105 and is moved toward the cover glass 20, until the lower flange 103" thereon engages the upper portion of the holder 97, by the contraction of the spring 106 which turns said arm 105 about the pin 107. The pin 107, in turn, is held by the arm 108 and is attached to the fixed bracket 109 which extends upward around the turret 32 from the frame 41 by the block 110. The holder 97 in each instance positions the roller 103 so that no variations can exist in the accuracy of the positioning thereby.

The indexing movement of the head 54 to station E only interrupts the flow of nitrogen to the cup 21 momentarily as the aperture 88 in the lower half 87 of the rotary valve comes into alignment with the aperture 88 in the upper half when said station is reached, and the opening 84' comes into alignment with the opening 85 at the new position of the spindle 56.

Following the indexing of the head 54 to station E, the manifolds 111 and 112 at opposite sides of the head 54 are lowered until the flames from the plurality of burners 113 carried by each, are directed onto the peripheral edge or flange 114 of the cover glass 20. All parts of the apparatus are then located as shown in Fig. 3 and the heating interval is continued until just before the head 54 is again indexed when the manifolds 111 and 112 and burners 113 are raised to clear the lamp and head 54. The manifolds 111 and 112 are supported by the pipes 115 and 116 respectively, which are attached to and extend through the bracket 117 and which are, although not shown, connected to a source of combustible gas mixture in the usual manner by a flexible hose slipped over the ends thereof. The bracket 117 is attached to the rod 118 which is slidably mounted in the bracket 109 and which is caused to actuate the burners 113 by movement of the arm 119 shown in Fig. 6, connected thereto by the link 120. The arm 119 in turn is fastened to shaft 121 supported by the bracket 122 extending from the frame 41 and is actuated by the duplicate shaft 121 of similar means at the next station F taken by the head 54 to which it is connected through universal joint 123. In order that the rod 118 and the burners 113 do not turn and swing from their positions, said rod 118 is held in place by the arm 124 which slidably engages the stud 125 extending from the bracket 109.

The next indexing movement of the turret 32 carries the head 54 into station F and results in the flange 114 of the cover glass 20 being heated still further by burners (not shown) attached to the manifolds 126 and 127. This combination of burners is a duplicate of those at station E and the manifolds 126 and 127 are lowered and raised prior to the next indexing motion to carry the burners to and from operating relation to the cover glass 20 by rotation of the shaft 121 (Fig. 6) at this station in the same manner as at station F. The shaft 121 is connected to a duplicate shaft 121 at the next succeeding station G by the universal joint 128, and is operated therefrom.

The next succeeding indexing movement of the head 54 brings it into station G and below two different sets of burners 130 and 131 which are mounted on the manifolds 132—133 and 134—135 respectively, as shown in Fig. 7. The manifolds 132, 133, 134 and 135 are supported by the pipes 136, 137, 138 and 139 respectively, which are attached to the bracket 140 and are carried down into operative relation to the cover glass 20 and cup 21 by movement of said bracket 140. The bracket 140 is mounted on a rod 141 which is held

in a vertical position by the bracket 142 and, as shown in Figs. 6 and 9, is operated by the lever 143 to which it is connected by the link 144. The lever 143 functions as the operating means both for the burners at this station and those at adjoining stations as it is attached to the shaft 121 at this station which is coupled to a similar shaft at the other stations. Said lever 143 is itself actuated by the lever 145 which is connected thereto through the link 146 and engages the ways of the cam 147 through the roller 148. The lever 145 turns about the pin 149 which is carried by the bracket 150 extending from the frame 41, whereas the cam 147 is turned by the main cam shaft 151 and makes one complete revolution between like intervals of each indexing period. The flange 114 of the cover glass 20 receives the full heating effect of the burners 130 in the manner of the burners at the preceding stations and, together with the burners 131 which are directed against the rim of said flange 114 and the cup 21, rapidly cause it to soften. The metal rollers 152, which are brought down onto the flange 114 at the same time that the burners 130 and 131 are positioned, apply pressure both downwardly and inwardly to the softened flange 114 causing all portions of said flange 114 to be pressed down against the edge of the cup 21 and into intimate contact with the entire edge. The said rollers 152, as shown in Figs. 7 and 8, are rotatively mounted on the arms 153 on the opposite ends of the beam 154 which is pivoted on the pin 155 and is actuated through the rod 156 to which said pin 155 is fastened by the block 157. The rod 156 is fastened to the lever 158 which is pivoted on the pin 159 carried by the bracket 140 in such a manner that the weights 160 on one end thereof partially counter balance the said rod 156 and parts mounted thereon so that the rollers 152 press against the cover glass 20 with the desired pressure. At the limit of downward movement of the rollers 152, the end of the screw 161 carried by the lever 158 butts against the bracket 140 and prevents further movement. The movement necessary to lower the rollers 152 onto the cover glass 20 and to raise them therefrom at the end of the period of operation, is caused by the vertical movement of the bracket 140 as said movement carries the lever 158 up into engagement with the roller 162 carried by the arm 163 extending from the bracket 142, causing the lever 158 to turn about pin 159. This construction causes the rollers 152 to be raised and lowered a greater amount than the burners 130 and 131 and provide greater clearance therebelow.

The sealing of the flange 114 of the cover glass 20 to the cup 21 usually takes place at station H, the next succeeding station, and is brought about by the additional heat produced by the fires of burners attached to the manifolds 164 and 165 which correspond to the burners 131 and manifolds 134 and 135 at station G. As in prior instances, the burners are moved to and from operative relation to the cover glass 20 and cup 21 between indexing movements by means comprising the bracket 166, the rod 167, lever 168 (Fig. 6) and the shaft 121 which is connected to the corresponding shaft 121 at station G by the universal joint 169. Only the flange 114 of the cover glass 20 is to be sealed to the periphery of cup 21 but the sealing operation is not completed in some instances until the next station J is reached.

At station J, as shown in Figs. 10 and 11, a set of burners 170 is again brought to operative relation to the peripheries of the cover glass 20 and

cup 21 which are now fused together and form what is hereinafter referred to as the seal 171. The burners 170 are mounted on the manifolds 172 and 173 which are connected to the bracket 174 on the upper end of the rod 175 by the pipes 176 and 177 respectively, and are moved to and from position by vertical motion thereof. The rod 175, as shown in Fig. 6, is actuated through a lever 178 and a shaft 121, which is connected to duplicate means at station H through the universal joint 179. The heating effect of the flames from the burners 170 assists both in finishing of the seal 171 and in keeping it heated so that it can be reshaped by the rolls 180 which are caused to move in thereagainst while the head 54 is at this station. The rolls 180 are attached to the arms 181 which are pivoted on the pins 182 carried by the beam 183 and are caused to swing in against the seal by the weights 184 which are located on the outer ends of the rods 185 extending from said arms 181. The rolls 180 round out the edge of the seal and reduce it to a uniform diameter determined by the position of the stop screws 186 which extend from the beam 183 and which are engaged by the inner ends of the rods 185 at the limit of motion of the rolls 180.

As clearance must be provided to allow the lamp and head 54 to index, the beam 183 and rolls 180 are separated from the lamp and raised before the head 54 is indexed out of this station. These movements are brought about by the vertical movement of the bracket 174 which is connected to the lever 187 through the link 188 and during the first portion of said movement causes the lever 187 to turn about the pin 189 so as to engage the inner ends of the rods 185 and swing the arms 181 and the rolls 180 away from the lamp. The pin 189 is fastened to the rod 190 supporting the beam 183 through the block 191 and further movement of the bracket 174 carries the head of the screw 192 on the lever 187 against said rod 190 lifting the beams 183, the rolls 180 and other means attached thereto, upward away from the lamp. The rod 190 is held by the arm 193 which is in turn pivotally mounted on the pin 194 extending from the bracket 195 and when lifted, turns said arm 193 about said pin 194. The lower position of the arm 193 which aligns the rolls 180 with respect to the lamp, is determined by the position of the screw 196 extending from the bracket 195 which limits the rotation of the arm 193 in one direction. The bracket 195 is a fixed member being attached to the frame of the machine and has the extensions 197 at opposite sides of the arm 193 to keep it and the means attached thereto in alignment with the head 54.

All operations required to seal the cover glass 20 and the cup 21 together and to form the seal 171 are now complete except for the operations taking place at station K. At this station (K) the seal 171 is stretched and worked to partially relieve it of strains, and the cover glass 20 is repositioned to cause the annular locating shoulder or embossment 24 to be separated from the annular reference seat 65 of the cup 21, so that additional strains are not produced in the seal 171 when the lamp cools. Both operations are produced by an upward movement of the cover glass 20 following an upward movement of the spindle 56 which causes the cup 21 to be supported by the fingers 59 of the holder 55 and also causes the positioning of the ring 198 or other stop means at a definite distance from a portion of the cover glass. The repositioning of the 70

spindle 56 takes place as the head 54 is moved into station K as the shoe 57 on the lower end thereof then engages and rides up an inclined portion (not shown) of the track 58.

As shown in Fig. 12, the ring 198 is rotatably mounted, through straps 198' and collar 199, on the lower end of the rod 199 and is held in a raised position during the indexing interval by the collar 200 on the upper end of said rod 199, which collar rests on the blocks 201 and 202 surrounding the adjacent portion of said rod 199. When the lamp is properly positioned below the ring 198, the blocks 201 and 202 are lowered by movement of the lever 203 which engages a groove 204 in each through the roller 205, and the weight of the rod 199 and ring 198 carries said ring 198 down into engagement with the peripheral flange 114 on the cover glass 20. The lever 203 is pivoted on the shaft 206 and is actuated through the rod 207 which, as shown in Fig. 14, is connected to the lever 208 actuated by the cam 209 on the main cam shaft 151. A spring 210 extends between the lever 208 and a portion of the frame (not shown) and turns said lever 208 about the shaft 211 carried by the bracket 212 (only partially shown) extending from the frame so that the roller 213 thereon engages the cam 209.

The lowering movement of the blocks 201 and 202 is greater than that required by ring 198, and it separates said blocks 201 and 202, which are held in place about the rod 199 by the plate 214 carried by the lever 203, from the collar 200 on the upper end thereof. In this manner the ring 198 is positioned with reference to the flange 114 of each cover glass 20 indexed into station K, irrespective of the position thereof, and a known movement upward of the ring and the rod 199 will space the ring a definite distance from the cover glass 20 (or its flange 114) in every instance. Such a movement of the ring 198 and rod 199 is produced, after the blocks 201 and 202 are caused to grip said rod 199 tightly by pressure exerted thereagainst, by the jaws 215 and 216 (Figs. 12 and 15) which are pivoted on the pins 217 extending from the lever 203 and which engage said blocks 201 and 202 through the rollers 218. The jaws 215 and 216 are caused to close on the said blocks 201 and 202 by the movement of the wedge 219 from between the rollers 220 carried by the outer ends thereof, which allows the contracting force of the spring 221 to close the jaws 215 and 216. The wedge 219 in turn is mounted on the shaft 206 which is carried by the bracket 222 and is shifted in and out from between the rollers 220 by the rotation thereof, the result of a change in shape of the cam 223 (Fig. 14) on the main cam shaft 151 which operates through the lever 224 on shaft 211, the rod 225 and the arm 226. A spring 227 in this instance turns the lever 224 so that the roller 228 thereon engages the cam 223. The upward movement of the blocks 201 and 202 and the ring 198 is brought about by the lever 203 which is actuated the required amount by a change in shape of the cam 209 and is followed by the gripping jaws 215 and 216 which are pivoted on the pins 217 carried by said lever 203 and which are located in the ways provided by the plate 229 attached thereto.

The distance of movement of the ring 198 represents the amount of displacement desired of the cover glass 20 and is usually of the order of .05 of an inch. This movement is sufficient to work the seal 171 in a manner to relieve some of the strain therein and to separate the annular

locating shoulder 24 from the reference seat 65 more than they will move toward each other when the seal 171 and the main portion of the cover glass 20 and cup 21 cool and contract. The locating shoulder 24 and the reference seat 65 5 position the cover glass 20 with respect to the cup 21 during the sealing operation, but being adjacent the seal portion 171 and not heated to nearly as high a temperature, do not contract as much as the seal 171 and must be separated to 10 allow the seal 171 to contract fully. The direction of contraction of the main portions of the cover glass 20 and cup 21 also draws the locating shoulder 24 and reference seat 65 toward each other so as to make it desirable to separate them. 15

In some instances it is also desirable to definitely limit the upward movement of the arm 203 to accurately position the ring 198 because of play in the operating system therefor. In such instances a stop screw 230 is mounted on the arm 203 and an arm 231 which is mounted on the shaft 232 carried by the bracket 233 extending from bracket 222 is moved into position above said screw 230 to prevent excess motion. The arm 231 is operated through the shaft 232 which is connected through the arm 234, rod 235, arm 236 (Fig. 14), shaft 237, arm 238 and rod 239 to the lever 224. The regular movements of the lever 224 are such that the first adjustment thereof turns the wedge 219, allowing the jaws 215 and 216 to close and a later adjustment thereof moves the arm 231 into position. 30

The upward movement of the cover glass 20 carrying it into contact with the ring 198 or other stop means, is brought about by the introduction of additional gas pressure into the lamp under preferably 100 mm. of mercury pressure, and is brought about by the adjustment of the valve 240 (Fig. 14). The valve 240 is comprised of a movable portion 241 which is connected to a lever 242 by the rod 243 and which is turned by movement of the cam 244 on the main cam shaft 151 with respect to roller 245 carried by the lever 242. The spring 246 which extends between said lever 242 and a portion of the frame (not shown) causes the said lever 242 which is mounted on the shaft 211 to keep the roller 245 against the cam 244. The supply of the gas, nitrogen in this case, under the desired pressure is connected to the movable portion 241 of the valve 240 through the pipe 247 and at this time an aperture leading thereto is carried into alignment with an aperture in the body 248 of the valve connected to the pipe 249 so that the gas passes therethrough. The pipe 249 in turn is connected to an aperture of the lower half 87 (Fig. 3) of the rotary valve 81 in alignment with the aperture 88 in the upper half 89 thereof leading to the head 54 at this station and gas flows into the lamp through the system comprising the pipe 90, the chamber 91, the aperture 85, the aperture 84 in alignment with the aperture 85 at this position of the spindle 56, and the passages 63 and 92 in said spindle 56 and the tube 61, respectively. 45

The gas passes into the lamp with such rapidity that a pressure is built up therein, even though it escapes through the exhaust tube 60 in the space surrounding the metal tube 61 and passes out of the head 54 between said lamp and the holder 55. After a relatively short interval the valve 240 is closed and the discharge of gas from the lamp rapidly reduces the pressure therein to atmospheric, whereupon the arm 231 is swung out of position above the screw 230 and the ring 198 is raised. The raising of the ring 198 is brought 50

about by additional upward movement of the lever 203 while the friction blocks 201 and 202 are still gripping the rod 199 tightly and it is not until the ring 198 is to be lowered that the jaws 215 and 216 are separated and the collar 200 drops down into contact with said friction blocks 201 and 202. 55

In addition to the operations required in relocating the cover glass 20, still another operation takes place at station K. This operation consists in the first annealing operation of a series brought about at this station and each of the five following stations L, M, N, O and P by the flames from the upper and lower banks 251 and 252 of burners located thereat. Figure 1 does not show these banks 251 and 252 of burners at station K clearly, as the upper bank 251 lies between stations K and L and the lower bank 252 lies radially outward from said station K and below a portion of the cover glass repositioning means. The indexing movement of the lamp from stations K to L again causes the head 54 to be raised to the same position it is located during the pre-heating of the lamp so that the cup 21 is carried higher above the holder 97 and can be reached more easily by the annealing fires. The motion of the spindle 56 is caused by the engagement of the shoe 57 on the lower end thereof with a second inclined portion of the track 58 carrying it up onto a portion parallel to that at 58' (Fig. 3). Although these banks 251 and 252 of burners at stations K, L, M, N, O and P direct a considerable quantity of heat onto the lamp, it loses heat more rapidly than it gains and gradually drops in temperature until further annealing is not required when station Q is reached. 30

In combination with the annealing operation performed at these latter stations L, M, N, O and P, the lamp is flushed with additional nitrogen, this time at but 15 mm. of mercury pressure and introduced in the same manner through the rotary valve 81 and the metal tube 61. The flushing results from the alignment of apertures in the lower half 87 of the rotary valve 81 with the aperture 88 in the upper half 89 and the realignment of the aperture 84 in the spindle 56 with the aperture 85 in the sleeve 71 at this position of the spindle 56, and completely clears the lamp of all gases and vapors other than the flushing gas used. Some of these gases and vapors were contained in the cover glass 20 and cup 21 until driven out by the heat of the sealing operation, and flushing the lamp at this moment prevents said gases from being absorbed again as the lamp 40 cools. 50

Station Q is the unloading station and the final station in the cycle of operation of the machine which is completed by a raising movement of the spindle 56 during the indexing motion of the head 54 into said station. The indexing motion carries the shoe 57 on the end of said spindle 56 up an inclined portion of the track 58 to the highest portion thereof opposite stations Q and A so that the lamp is raised above the holder 97 and can easily be removed from holder 55 without danger of touching the hot mechanism. The flushing gas remains in the lamp and protects it from contamination prior to final exhausting and gas filling thereof. 60

What I claim as new and desire to secure by Letters Patent of the United States is:

1. A sealing machine of the character described comprising a head for supporting a vitreous cup with its peripheral edge uppermost and a cover glass resting thereon with a peripheral edge 70

- in contact with said cup edge, a carrier for supporting said head and advancing it into each of a plurality of stations in turn, means located at one of said stations for pre-heating the whole of said cup and cover glass, and means located at a succeeding station for intensely heating the peripheral edges of said cup and cover glass to cause them to be fused together.
2. A sealing machine of the character described comprising a head for supporting a vitreous cup with its peripheral edge uppermost and a cover glass resting thereon with a peripheral edge in contact with said cup edge, a carrier for supporting said head and advancing it into each of a plurality of stations in turn, means located at one of said stations for pre-heating the whole of said cup and cover glass, means located at a succeeding station for intensely heating the peripheral edges of said cup and cover glass to cause them to be fused together, and means at another succeeding station for heating the whole of said cup and cover glass to reduce the rate of cooling thereof and cause them to be annealed.
3. A sealing machine of the character described comprising a head for supporting a vitreous cup with its peripheral edge uppermost and a cover glass resting thereon with a peripheral edge in contact with said cup edge, said head having a ring-shaped holder engaging substantially the whole of an annular portion of said cup adjacent its edge, a carrier for supporting said head and advancing it into each of a plurality of stations in turn, and means located at one of said stations for fusing the peripheral edges of the cup and cover glass together.
4. A sealing machine of the character described comprising a head having a holder for supporting a vitreous cup with its peripheral edge uppermost and a cover glass resting thereon with a peripheral edge in contact with said cup edge, said head comprising also a second ring-shaped holder adapted to engage substantially the whole of an annular portion of said cup adjacent its edge, a carrier for supporting said head and advancing it to each of a plurality of stations in turn, means located at one of said stations for pre-heating the whole of said cup and cover glass, means located along the path of movement of said head for causing a relative vertical movement between said holders to cause the said cup to be rested on the said second ring-shaped holder, and means located adjacent the path of movement of said head for fusing the peripheral edges of said cup and cover glass together.
5. A sealing machine of the character described comprising a head for supporting a vitreous cover glass, a carrier for supporting said head and advancing it along a predetermined path, means located along said path for pre-heating said cover glass, a second carrier for supporting and advancing said first carrier, a second head mounted on said second carrier for supporting a vitreous cup with its peripheral edge uppermost so that it supports a cover glass transferred from the said first-mentioned head and rested on said cup with the peripheral edge of said cover glass in contact with said cup edge, and means located at a station into which the said second-mentioned head is advanced for fusing the peripheral edges of said cup and cover glass together.
6. A sealing machine of the character described comprising a head for supporting a vitreous cup with its peripheral edge uppermost and a cover glass resting thereon with a peripheral edge in contact with said cup edge, said head having a 15 ring-shaped holder engaging the portion of said cup adjacent its edge, a carrier for supporting said head and advancing it into each of a plurality of stations in turn, means located at one of said stations for causing said head to be rotated on the carrier, means engaging the periphery of said holder and the peripheral edge of said cover glass at said station for positioning said cover glass laterally with respect to said holder and the said cup to center it on said cup as the head rotates, and means located adjacent the path of movement of said head for fusing the peripheral edges of said cup and cover glass together.
7. A sealing machine of the character described comprising a head for supporting a vitreous cup with its peripheral edge uppermost and a vitreous cover glass rested thereon with a peripheral edge in contact with said cup edge, a carrier for advancing said head into each of a plurality of stations in turn, means located at one of said stations for heating the peripheral edge of said cover glass to render it plastic, means for pressing the said plastic edge tightly into intimate contact with the peripheral edge of said cup during rotation thereof, and means adjacent the path of movement of said head for fusing the said edges of said cup and cover glass together.
8. A sealing machine of the character described comprising a rotatable head for supporting a vitreous cup with its peripheral edge uppermost and a vitreous cover glass rested thereon with a peripheral edge in contact with said cup edge, a carrier for supporting said head and advancing it into each of a plurality of stations in turn, means located at one of said stations for rotating said head and means also located at said station for heating the peripheral edge of said cover glass, a vertically disposed roller having an oblique face also located at said station, means for moving said roller down against the outer edge of said cover glass to cause it to be pressed downward and inward into intimate contact with the edge of said cup during rotation thereof, and means adjacent the path of movement of said head for fusing the said edges of said cup and cover glass together.
9. A sealing machine of the character described comprising a rotatable head for supporting a vitreous cup with its peripheral edge uppermost and a vitreous cover glass rested thereon with a peripheral edge in contact with said cup edge, a carrier for supporting said head and advancing it into each of a plurality of stations in turn, heating means located at one of said stations for fusing the peripheral edges of said cup and cover glass together, means at another of said stations for rotating said head, and means also at said last-mentioned station engaging the peripheral edges of said cup and cover glass and reducing them to a predetermined uniform size and shape during the rotation of the said head.
10. A sealing machine of the character described comprising a rotatable head for supporting a vitreous cup with its peripheral edge uppermost and a vitreous cover glass rested thereon with a peripheral edge in contact with said cup edge, a carrier for advancing said head into each of a plurality of stations in turn, heating means located at one of said stations for fusing the peripheral edges of said cup and cover glass together, rolls located at said station, and means for moving said rolls laterally against the said peripheral edges of said cup and cover glass at opposite sides thereof to cause said peripheral

edges to be reduced to a predetermined uniform size and shape during the rotation of the said head.

11. A sealing machine of the character described comprising a rotatable head for supporting a vitreous cup with its peripheral edge uppermost and a vitreous cover glass rested thereon with a peripheral edge in contact with said cup edge, a carrier for supporting said head and advancing it into each of a plurality of stations in turn, means located at one of said stations for heating the peripheral edge of said cover glass to render it plastic, means for pressing the said plastic edge tightly into intimate contact with the peripheral edge of said cup during rotation thereof, heating means located adjacent the path of travel of said head for fusing the said edges of said cup and cover glass together, means for rotating said head during said fusing operation and means operable to engage the peripheral edges of said cup and cover glass to reduce said edges to a predetermined uniform size and shape during the rotation of said head.

12. A sealing machine of the character described comprising a rotatable head for supporting a vitreous cup with its peripheral edge uppermost and a vitreous cover glass rested thereon with a peripheral edge in contact with said cup edge, a carrier for supporting said head and advancing it into each of a plurality of stations in turn, means located at one of said stations for heating and working the peripheral edges of said cup and cover glass during rotation thereof to cause them to be sealed together, and means for first lowering said last-named means into operative relation to said head and to the cup and cover glass thereon and then raising it therefrom between advancing movements of said head from station to station.

13. A sealing machine of the character described comprising a head for supporting a vitreous cup having a reflecting coating on the interior thereof with the peripheral edge of said cup uppermost and supporting a cover glass at its peripheral edge, a carrier for supporting said head and advancing it into each of a plurality of stations in turn, means at one of said stations for pre-heating the whole of said cup and cover glass, means at said station operable in combination with said head and the carrier for causing the atmosphere enclosed by said cover glass and cup to be replaced with an inert gas to protect the reflecting coating on said cup, and means located at one of said stations for fusing the peripheral edges of said cup and cover glass together.

14. A sealing machine of the character described comprising a head for supporting a vitreous cup having a reflecting coating on the interior thereof with the peripheral edge of said cup uppermost and supporting a cover glass at its peripheral edge, a carrier for supporting said head and advancing it into each of a plurality of stations in turn, means at one of said stations for pre-heating the whole of said cup and cover glass, means at another station for fusing the peripheral edges of said cup and cover glass together, means at a succeeding station for heating the whole of said cup and cover glass to reduce the rate of cooling and cause them to be annealed, and means at the pre-heating and annealing stations and operable in combination with said head and carrier for causing the atmosphere in the enclosure formed by said cover glass and cup to be replaced and to flush the

said enclosure so as to protect the reflecting coating on said cup and clear said enclosure of injurious gases and vapors.

15. A sealing machine of the character described comprising a head for supporting a vitreous cup having an exhaust tube depending therefrom with the peripheral edge of said cup uppermost and supporting a cover glass at its peripheral edge, a tube attached to the head and arranged to extend upwardly within said exhaust tube and into the said cup, a carrier for supporting said head and advancing it into each of a plurality of stations in turn, means operable in combination with said head and carrier for causing an inert gas to be conducted through said second-mentioned tube into the enclosure formed by said cover glass and cup to expel the atmosphere therein through the space between the said second-mentioned tube and said exhaust tube, and means adjacent the path of travel of said head for fusing the peripheral edges of said cup and cover glass together.

16. A sealing machine of the character described comprising a head including a hollow spindle having a holder thereon for supporting a vitreous cup with the peripheral edge of said cup uppermost and supporting a cover glass at its peripheral edge, the interior of said spindle being in communication with the interior of said cup, a carrier for supporting said head and advancing it into each of a plurality of stations in turn, means located at one of said stations for fusing the peripheral edges of said cup and cover glass together, means operable in combination with said head and carrier for causing a gas to be introduced through the interior of said spindle into the enclosure formed by said cover glass and cup under sufficient pressure to cause a relative movement between said cup and cover glass to thereby stretch the plastic sealed edges thereof and cause some strains to be removed therefrom and the said cover glass to be repositioned.

17. A sealing machine of the character described comprising a head including a hollow spindle having a holder thereon for supporting a vitreous cup with the peripheral edge of said cup uppermost and supporting a cover glass at its peripheral edge, the interior of said spindle being in communication with the interior of said cup, a carrier for supporting said head and advancing it into each of a plurality of stations in turn, means located at one of said stations for fusing the peripheral edges of said cup and cover glass together, means operable in combination with said head and carrier for causing a gas to be introduced through the interior of said spindle into the enclosure formed by said cover glass and cup under sufficient pressure to cause a relative movement between said cup and cover glass to thereby stretch the plastic sealed edges thereof and cause some strains to be removed therefrom, and means for limiting the movement of said cover glass with respect to said head to definitely reposition it.

18. A sealing machine of the character described comprising a head for supporting a vitreous cup with its peripheral edge uppermost and supporting a cover glass at its peripheral edge, a carrier for supporting said head and advancing it into each of a plurality of stations in turn, means located at one of said stations for fusing the peripheral edges of said cup and cover glass together, stop means located at a succeeding station above said head, means for first lowering

said stop means into contact with the peripheral edge of the cover glass in said head and then raising it a definite distance therefrom, and means operable in combination with said head and carrier for causing a gas to be introduced into the enclosure formed by said cover glass and cup under sufficient pressure to raise said cover glass and bring its peripheral edge into engagement with said stop means to thereby stretch the plastic sealed edges and cause the said cover glass to be repositioned.

19. A sealing machine of the character described comprising a head having a holder for supporting a vitreous cup with its peripheral edge uppermost and supporting a cover glass at its peripheral edge, and a second ring-shaped holder adapted to engage that portion of said cup adjacent its edge, a carrier for supporting said head and advancing it into each of a plurality of stations in turn, means at one of said stations, for pre-heating the whole of said cup and cover glass, means located along the path of movement of said head for causing said first-mentioned holder to be lowered to transfer said cup to the said ring-shaped holder, means at another station for sealing the peripheral edges of said cup and cover glass together, means operable in combination with said head and carrier for causing a gas to be introduced into the enclosure formed by said cover glass and cup under sufficient pressure to raise the said cover glass and thereby stretch the plastic sealed edges of said cup and cover glass to remove some of the strain therefrom, and means for limiting the movement of said cover glass to definitely position it with respect to said cup.

20. In a sealing machine of the class described, a head for supporting a vitreous cup with its peripheral edge uppermost and a vitreous cover glass rested thereon with a peripheral edge in contact with said cup edge, said head comprising a vertically disposed spindle carrying at its upper end a holder for said cup having means for engaging terminal elements projecting from said cup to definitely orient the cup, a ring-shaped holder on said head adapted to receive said cup and support it adjacent its periphery and having a notch at its edge arranged to engage a lug on the edge of said cup, and means for lowering said spindle to carry the cup down into engagement with said ring-shaped holder so that said lug engages said notch.

21. A sealing machine of the character described comprising a movable carrier, a head on said carrier for supporting a vitreous cup with its peripheral edge uppermost and a vitreous cover glass rested thereon with a peripheral edge in contact with said cup edge, said head comprising a vertically disposed spindle carrying a holder at

its upper end for supporting said cup and a ring-shaped holder therebelow adapted to receive said cup and support it adjacent its periphery, means for rotating said head about the axis of said spindle, means adjacent the path of travel of said head for preheating said cup and cover glass, means for subsequently causing said spindle to move downward to carry the holder thereon down within said ring-shaped holder and rest the cup thereon, means for then intensively heating the peripheral edges of said cup and cover glass to soften them, vertically disposed rollers mounted above the path of travel of said head, means for moving said rollers down against the edge of said cover glass to press it into intimate contact with the edge of said cup, reshaping rolls mounted adjacent the path of travel of said head, and means for moving said rolls laterally against the edges of said cup and cover glass to reduce them to a predetermined diameter and shape.

22. A sealing machine of the character described comprising a movable carrier, a head on said carrier for supporting a vitreous cup with its peripheral edge uppermost and a vitreous cover glass rested thereon with a peripheral edge in contact with said cup edge, said head comprising a vertically disposed spindle carrying a holder at its upper end for supporting said cup and a ring-shaped holder therebelow adapted to receive said cup and support it adjacent its periphery, means for rotating said head about the axis of said spindle, means adjacent the path of travel of said head for preheating said cup and cover glass, means for subsequently causing said spindle to move downward to carry the holder thereon down within said ring-shaped holder and rest the cup thereon, means for then intensively heating the peripheral edges of said cup and cover glass to soften them, vertically disposed rollers mounted above the path of travel of said head, means for moving said rollers down against the edge of said cover glass to press it into intimate contact with the edge of said cup, reshaping rolls mounted adjacent the path of travel of said head, means for moving said rolls laterally against the edges of said cup and cover glass to reduce them to a predetermined diameter and shape, a stop member located above the path of travel of said head, means for positioning said stop member a small predetermined distance above the cover glass in said head, and means for causing a gas to be introduced into the enclosure formed by said cover glass and cup under sufficient pressure to raise said cover glass into engagement with said stop means to thereby stretch the plastic sealed edges and cause the cover glass to be repositioned.

FRANK J. MALLOY.
